His Attorney.

UNITED STATES PATENT OFFICE.

CHARLES L. PERRY, OF SCHENECTADY, NEW YORK, ASSIGNOR TO GENERAL ELECTRIC COMPANY, A CORPORATION OF NEW YORK.

ELECTRIC SWITCH.

Application filed January 21, 1921. Serial No. 438,993.

To all whom it may concern:

Be it known that I, CHARLES L. PERRY, a citizen of the United States, residing at Schenectady, in the county of Schenectady, 5 State of New York, have invented certain new and useful Improvements in Electric Switches, of which the following is a specification.

My invention relates to electric switches 10 and in particular to improvements in the contact mechanism thereof.

Although not necessarily limited thereto, my invention has a particular application to electric switches adapted to make and 15 break circuits carrying heavy current.

One of the objects of my invention is to provide improved self-aligning contact mechanism which shall always offer a large and uniform bearing surface for the contacts.

In carrying my invention into effect in one form, I hold one of the contacts resiliently in position in a support in such a manner that the contacts may freely align 25 themselves and a spring pressure is set up between the contacts in their closed position.

For a better understanding of my invention, reference is had to the accompanying drawings which show an embodiment of my

30 invention for purposes of illustration, and in which Fig. 1 is a side view of an electromagnetic switch in the closed position; Fig. 2 is a cross-sectional detail of the main switch contacts in the closed position; Fig. 35 3 is a perspective view of the support in which one of the contacts is mounted; and Fig. 4 is a perspective view of the contact which cooperates with the support shown in Fig. 3.

40 Referring to the drawings, the switch mechanism is mounted upon an insulating base 10 and the switch is operated by means of an operating electromagnet 11 having an armature 12 pivotally mounted at 13 and 45 connected to the switch contact 14, one of the two relatively movable engaging main contacts of the switch which have substantially flat engaging surfaces. This contact 14 is adapted to make engagement with the 50 main contact 15 which is positioned in what amounts to a three-point support. This support comprises the upper hinge support 16, the stop 17, and the spring 18 which is positioned between the upper hinge support 55 and the stop substantially opposite the mid-

position of the engaging surfaces of the main contacts so as to press on the contact at right angles to the plane of engagement of the contacts. The upper hinge support, comprising the shaft 19 which serves 60 as the pintle of the hinge construction, and the U-shaped member 20 which has an extension 21 secured to the switch contact, is adapted to cooperate with the pintle 19 so as to hold the resiliently mounted switch 65 contact 15 in position. The stop 17 also cooperates with the upper hinge support and the spring 18 to hold the contact 15 in position when the switch is open. The U-shaped member 20 of the hinge construction is arranged so that the movement of the contact 15 toward the contact 14 is limited in the open position of the switch and when the switch closes, the contact 15 is permitted to move along the line of movement of the contacts 70 against the pressure of the spring 18. The contact 15 is permitted to tilt in all directions with the spring support as the fulcrum of the tilting movement. The contact 15 is connected to the main switch terminal 22 by means of the flexible conductor 23, and the main contact 14 is connected to the switch terminal 24 by means of the flexible conductor 25.

75 The auxiliary switch contact 26 is pivotally mounted with respect to the main contact 14 at 27, and is resiliently held in position by means of the spring 28 which cooperates with the bolt 29 secured to the arm 30 connected to the main contact 14. The auxiliary or arcing contact 26 is adapted 80 to make engagement with the stationary contact 31 which is connected to a blow-out coil 32. The auxiliary or arcing contact 26 is connected to the main switch terminal 24 by means of the flexible conductor 33. It will be understood by those skilled in the art that the construction of the switch contacts is such that auxiliary or arcing contacts 26 and 31 first make engagement when 85 the switch is being closed, and finally the main contacts 14 and 15 make engagement, and that in the opening of the switch the main contacts 14 and 15 first open and the electric circuit controlled by the switch is 90 opened subsequently by the opening of the arcing contacts 26 and 31. The arcs formed upon the interruption of the electric circuit are disrupted by being magnetically blown 95 through the arc chute 34.

As thus constructed and arranged, the operation of my invention is as follows:—Assume that the switch is in the open position at which the main contacts 14 and 15 are out of engagement and the arcing contacts 26 and 31 are also out of engagement. The armature 12 will be attracted by the core of the operating electromagnet 11 and turn the switch contacts 14 and 26 counter-clockwise until the arcing contacts 26 and 31 make engagement. The completion of the movement of the armature 12 to the attracted position will cause the main contact 14 to make engagement with the main contact 15. The main contact 15 will be moved in the line of movement of the main contact 14 and in case the engaging surfaces of the contacts are not in exact alignment when the main contacts first make engagement, the contact 15 will be permitted to tilt with respect to the hinge support 16 about the spring 18 as a fulcrum point so as to accurately align the main contacts and at the same time to set up a spring pressure between the contacts. By reason of the fact that the main contacts 14 and 15 are completely self-aligning, burning, heating and unequal wear of the contacts are prevented.

When the electromagnet 11 is deenergized, the armature 12 will be released and will be permitted to rotate clockwise so as to carry the main contact 14 and the auxiliary contact 26 out of engagement with their respective cooperating contacts. The pressure of the spring 18 will be partially relieved and the main contact 15 will return to its original position and be held against the pintle 19 and the bar 35 which cooperates with the stop 17.

It will be understood by those skilled in the art from the above description of my invention that my invention has features of simplicity of construction and arrangement and is nevertheless effective in operation.

In accordance with the provisions of the patent statutes, I have described the principle of operation of my invention, together with the apparatus which I now consider to represent the best embodiment thereof, but I desire to have it understood that the apparatus shown is only illustrative and that the invention can be carried out by other means.

What I claim as new and desire to secure by Letters Patent of the United States, is:—

1. In an electric switch, two relatively movable engaging switch contacts, a support for one of the contacts arranged to permit the tilting thereof and the movement thereof with respect to the support along the line of movement of the contacts, and a spring put under strain by the closing of the switch and adapted to press on the said contact at a substantially mid-position of the engaging surfaces of the contacts for biasing

the said contact toward the other contact and for providing a resilient fulcrum for the said contact to accurately align itself with the other contact.

2. In an electric switch, two relatively movable engaging switch contacts, a hinge support for one of the contacts arranged to permit the movement of the contact along the line of movement of the contacts and the tilting of the contact for accurately aligning the engaging surfaces of the contacts, a stop cooperating with the support for positioning the said contact, and a spring between the said support and stop for holding the said contact against the support and stop in the open position of the switch and adapted to be put under strain by the closing of the switch.

3. In an electric switch, two relatively movable engaging switch contacts, a support for one of the contacts, a stop cooperating with the support for positioning the said contact, a spring between the said support and stop for holding the said contact against the support and stop in the open position of the switch and adapted to be put under strain by the closing of the switch, the said support and stop arranged to permit the movement of the said contact along the line of movement of the contacts and the tilting of the said contact about the spring as a fulcrum for accurately aligning the engaging surfaces of the contacts.

4. In an electric switch, two relatively movable engaging switch contacts, an upper support for one of the contacts, a lower support for the same, a spring between the supports for holding the said contact against its supports and adapted to be put under strain by the closing of the switch, the said supports arranged to limit the movement of the said contact toward the other contact and permit the movement of the said contact along the line of movement of the contacts and the tilting of the said contact about the spring as a fulcrum for accurately aligning the engaging surfaces of the contacts.

5. In an electric switch, two relatively movable engaging switch contacts, three aligned supports for supporting one of the contacts, the said supports arranged to limit the movement of the contact toward the other contact and permit the tilting of the contact and the movement thereof in the line of movement of the contacts, and a spring serving as the middle of the three supports interposed back of a substantial mid-position of the engaging surfaces of the contacts and adapted to be put under strain by the engagement of the contacts, whereby the contact is resiliently held in position and is permitted to fulcrum about the spring to align itself with the other contact.

6. In an electric switch two movable

- switch contacts having substantially flat engaging surfaces, the first of which is pivotally mounted and movable into engaging relation with the second of said contacts, a hinge support for the second of the contacts arranged to permit the movement of the second contact along the line of movement of the contacts and the tilting of the second contact about the support for accurately aligning the engaging surfaces of the contacts, a stop cooperating with the said sup-

port for positioning the second contact, and a spring acting on the said second contact between the said support and stop for holding the second contact against the support and stop in the open position of the switch and adapted to be put under strain by the closing of the switch.

In witness whereof, I have hereunto set my hand this 20th day of January 1921.

CHARLES L. PERRY.
